UNITED STATES PATENT OFFICE.

WILLIAM C. BAXTER, OF ROCHESTER, NEW YORK, ASSIGNOR TO EDWARD M. TRIMBLE,
OF ROCHESTER, NEW YORK.

CRIB.

Application filed August 9, 1922. Serial No. 580,756.

To all whom it may concern:

Be it known that I, WILLIAM C. BAXTER, a citizen of the United States, and resident of Rochester, in the county of Monroe and 5 State of New York, have invented certain new and useful Improvements in Cribs, of which the following is a specification.

The present invention relates to cribs and more particularly to the type in which a 10 bottom or mattress supporting member is adapted to occupy a plurality of horizontal positions within the crib body.

An object of this invention is to provide 15 upper position supporting means for the bottom or mattress supporting member in the form of rests normally lying in positions to project beneath the mattress supporting member and displaced from such positions when the mattress supporting member is 20 moved upwardly past them. Another object of the invention is to provide means preferably carried by the mattress supporting member for displacing the rests at the opposite ends of the mattress supporting 25 member when it is desired to lower said mattress supporting member.

To these and other ends, the invention 30 consists of certain parts and combinations of parts, all of which will be hereinafter described, the novel features being pointed out in the appended claims.

In the drawings:

Fig. 1 is a plan view of the crib in operative condition;

Fig. 2 is a plan view of the crib in folded condition;

Fig. 3 is a vertical sectional view through the crib showing the bottom member supported in the uppermost position;

Fig. 4 is a fragmentary view of the under side of one end of the bottom member;

Fig. 5 is a vertical section through the crib in folded condition;

Fig. 6 is an enlarged fragmentary section 45 showing the manner in which the displacing means cooperates with the rests in displacing the latter to permit the lowering of the bottom member;

Fig. 7 is a rear view of one of the rests 50 showing the manner in which it is mounted on its supporting plate;

Fig. 8 is a fragmentary view showing a supporting plate with the two rests thereon; and

Fig. 9 is a section on the line 9—9, Fig. 6.

Referring to the embodiment of the invention herein illustrated, 1 and 2 indicate two side walls which are connected together by end walls constructed to permit the side walls to move toward and from each other 60 in parallel relation. The end walls, in this instance, embody rigid sections 3 secured to the side walls 1, and hinged sections 4 and 5, the former being hinged at 6 to the rigid sections 3 and the sections 5 being hinged 65 at 7 to the hinged section 4 and also at 8 to the side wall 2.

In order to support the bottom or mattress supporting frame 9 in a lower horizontal position, a lower position supporting means 70 is provided preferably in the form of rails 10 and 11. The rail 10 connects with the rigid sections 3 and the side wall 1, while the rail 11 is connected to the side wall 2. The rail 10 is of such a width that the bottom 75 or mattress supporting member may swing thereon to a vertical position, as illustrated in Figs. 1 and 2, and in order to prevent this bottom member slipping off the rail 10, the latter has a lip or upstanding portion 12 at its free edge.

The upper position supporting means for the bottom or mattress supporting member embodies rests 13, which are movably mounted on the crib frame and are displaceable by the bottom or mattress supporting member, when the latter is moved upwardly, so that said bottom or mattress supporting member may cooperate with said rests. In this instance, the rests are arranged in two pairs at each end of the crib, one pair at each end being below another pair at the same end and horizontally aligned with a pair at the opposite end. These rests are, in this instance, pivoted 90 at 14 below their resting surfaces 15 and are formed with displacing faces 16 leading from the resting surfaces 15 substantially to the pivot. Each rest, in this instance, is stamped from sheet metal to provide side 95 flanges, through which the pivot 14 extends, the displacing wall 16 and the resting surface 15 as well as a lip 17 projecting upwardly from the resting surface at the inner end of the latter. To rests, one above the 100 other, at one end and one side of the crib are mounted on a single supporting plate 18 which is secured over a recess 19 in a side wall 1 or 2 and this supporting plate is provided with two openings and one pair 110

of ears 20 adjacent the lower end of each opening. The pivot pin 14 for a rest is supported by the ears and the rest projects through the adjacent opening, so that the lip 17 will cooperate with the rear face of the supporting plate 18 and limit the outward movement of the rest. Two springs 21 are secured to each plate 18 below openings therein and project upwardly to operate with the inner face of the rests, in order to give the latter a tendency to lie normally in positions to support the bottom or mattress supporting member. It is apparent that, when either end of the bottom or mattress supporting member is elevated, the sides of the mattress supporting member will move the rests inwardly until the bottom or mattress supporting member has passed over the rests, after the latter is moved outwardly under the springs 21 so that, when the mattress supporting member is released, it will be held by the rests directly beneath such mattress supporting member. After one end of the mattress supporting member is elevated to a pair of rests, the other end is moved upwardly to be positioned upon those rests at the opposite end of the frame, horizontally aligned with the rests on which the other end of the mattress supporting member is arranged.

With the end in view of providing means for simultaneously displacing two of the rests upon which one end of a mattress supporting frame is arranged, suitable means is provided preferably arranged upon the mattress supporting frame. In this instance, each end of the mattress supporting frame has rest displacing means thereon. This rest displacing means in the illustrated construction embodies two sliding rods 22 arranged at each end of the frame preferably in a transversely extending groove 23 on the under side of said end. Each of these rods has an end portion 24 projected below the under surface of the frame, so that the extreme end of said deflected portion will lie opposite the displacing face 16 of the rest, when the mattress supporting frame is resting upon such rest. In order to give the operating end of the displacing rod a position where it will not interfere with the rests, said end is held inwardly with reference to the adjacent side of the mattress supporting frame. This result is accomplished, in this instance, by overlapping the inner ends of the rods 22 and providing said ends with operating portions 25, which project upwardly preferably through slots 26 in a plate 27 which is secured over an opening 28, leading through the top of the mattress supporting frame to the transverse groove 23. Between the upwardly projecting ends 25 of the displacing rods, a helically formed spring 29 is positioned, this being held between two lugs 30 bent downwardly from

the plate on opposite sides of the spring, thus confining the spring in position above the displacing rods.

The operation of the invention will be understood from the foregoing, but it may be summarized as follows: Assuming that it is desired to collapse the crib, while the mattress supporting frame is resting upon the lower position supporting means 10 and 11, the mattress supporting frame with the mattress thereon is swung upwardly on the rail 10 to the positions illustrated in Figs. 1 and 3; thereafter the side walls are folded inwardly, as shown in Figs. 1 and 3. The displacing rods by lying within the sides of the mattress supporting frame do not interfere with this tilting movement of the mattress supporting frame and the rests by being yieldingly mounted move inwardly so as not to restrict the space between the side walls 1 and 2 when the crib is collapsed. Assuming that the mattress supporting frame lies upon the lower position supporting rails 10 and 11 and it is desired to elevate the mattress supporting frame to a higher horizontal position, say the uppermost position, one end of the mattress supporting frame is lifted until it passes both pair of rests at such end, displacing such rests inwardly, and the rests, after the passing of the end being projected outwardly under the action of their springs. When the end is released, it falls upon two of the rests 15 and is held by such rests. Thereafter the other end of the mattress supporting frame is elevated to pass above the rests at the opposite end and is held in the same manner as the first operated end of the frame. The mattress supporting frame can be lowered by pressing together the operating portions 25 at one end of the frame, thus displacing the rests on which this end of the frame is supported. When the next pair of rests is again reached, the operating portions 25 are again operated until this end of the mattress supporting frame comes to rest on the lower position supporting rails 10 and 11. Thereafter the displacing rods at the other end of the mattress supporting frame are manipulated in the same manner to lower such end.

From the foregoing it will be seen that there has been provided in a crib in which the side walls fold into parallel relation and the bottom or mattress supporting member is adapted to swing on the lower position supporting means to a position parallel with such side walls, an upper position supporting means in the form of displaceable rests. These rests, for one position of the crib are arranged in two pairs, one pair at each end of the crib. They are not only displaced by the movement of the mattress supporting frame upwardly, but provision is made whereby a pair of rests at each end of the crib may be simultaneously displaced to

lower the mattress supporting frame. This displacing means for lowering of the frame is preferably mounted on the mattress supporting frame and comprises in the illustrated embodiment a pair of rods which are controllable simultaneously at the center of the end and have their outer ends normally lying within the sides of the mattress supporting frame.

10. What I claim as my invention and desire to secure by Letters Patent is:

1. A crib comprising side walls, end walls connecting said side walls, lower position supporting means, a bottom member removable upwardly from the lower position supporting means, upper position supporting means for the bottom member embodying rests on the crib displaceable by the upward movement of said bottom member and having normal tendencies to lie in supporting positions, and movable rest displacing means carried by said bottom member to displace the rests while the bottom member is sustained on such rests to permit the lowering of the bottom member.

2. A crib comprising side walls, end walls connecting said side walls, lower position supporting means, a bottom member removable upwardly from the lower position supporting means, a pair of rests at each end of the crib, said rests each having a normal tendency to lie in supporting position and being displaceable by the bottom member when the latter is moved upwardly from the lower position supporting means, and rest displacing means at opposite ends of the crib for simultaneously displacing the members of each pair of rests at such end to permit the lowering of the bottom member.

3. A crib comprising side walls, end walls connecting said side walls, lower position supporting means, a bottom member removable upwardly from the lower position supporting means, a pair of rests at each end of the crib, said rests each having a normal tendency to lie in supporting position and being displaceable by the bottom member when the latter is moved upwardly from the lower position supporting means to permit the lowering of the bottom member and rest displacing means at opposite ends of the crib for simultaneously displacing the members of each pair of rests at such end to permit the lowering of the bottom member, said rest displacing means being mounted upon the bottom member.

4. A crib comprising side walls, end walls connecting said side walls, lower position supporting means, a bottom member removable upwardly from the lower position supporting means, a pair of rests at each end of the crib, said rests, each having a normal tendency to lie in supporting position and being displaceable by the bottom member when the latter is moved upwardly from

the lower position supporting means, and rest displacing means mounted upon the bottom member and having displacing portions for cooperating with said rests, normally lying within the lines of the sides of 70 the bottom member.

5. A crib comprising side walls, end walls connecting said side walls, lower position supporting means, a bottom member removable upwardly from the lower position supporting means, a pair of rests at each end of the crib, said rests, each having a normal tendency to lie in supporting position and being displaceable by the bottom member when the latter is moved upwardly from 80 the lower position supporting means, and a pair of displacing rods mounted at each end of the bottom member and movable in opposite directions to effect the displacement.

6. A crib comprising side walls, end walls connecting said side walls, lower position supporting means, a bottom member removable upwardly from the lower position supporting means, a pair of rests at each end of the crib, said rests, each having a normal 90 tendency to lie in supporting position and being displaceable by the bottom member when the latter is moved upwardly from the lower position supporting means, a pair of displacing rods mounted at each end of the 95 bottom member and movable in opposite directions to effect the displacement, and a spring common to both of said displacing rods for holding them out of displacing position and within the lines of the sides of 100 the bottom member.

7. A crib comprising side walls, end walls connecting said side walls, lower position supporting means, a bottom member removable upwardly from the lower position supporting means, a pair of rests at each end of the crib, said rests, each having a normal tendency to lie in supporting position and being displaceable by the bottom member when the latter is moved upwardly from the 105 lower position supporting means, the bottom member having on its under side transverse grooves near opposite ends, two rest-displacing rods mounted in each groove and overlapping at their inner ends, said rods having their outer ends provided with portions deflected downwardly below the surface of the bottom member engaging the rests, and having upwardly extending operating portions at their inner ends.

8. A crib comprising side walls, end walls connecting said side walls, lower position supporting means, a bottom member removable upwardly from the lower position supporting means, a pair of rests at each end of the crib, said rests, each having a normal tendency to lie in supporting position and being displaceable by the bottom member when the latter is moved upwardly from 125 the lower position supporting means, the 130

bottom member having on its under side transverse grooves near opposite ends, two rest-displacing rods mounted in each groove and overlapping at their inner ends, said rods having their outer ends provided with

rests, and having upwardly extending operating portions at their inner ends, and a spring interposed between said rods for normally holding them in non-displacing position.

WILLIAM C. BAXTER.
